UNITED STATES PATENT OFFICE.

LEWIS C. HUNTER, OF DETROIT, MICHIGAN.

DISAPPEARING BED.

1,244,736.

Specification of Letters Patent. Patented Oct. 30, 1917.

Application filed June 21, 1915. Serial No. 35,353.

To all whom it may concern:

Be it known that I, LEWIS C. HUNTER, a citizen of the United States of America, residing at Detroit, in the county of Wayne 5 and State of Michigan, have invented certain new and useful Improvements in Disappearing Beds, of which the following is a specification, reference being had therein to the accompanying drawings.

10 This invention relates to a disappearing bed of that type adapted to be folded and swung into a closet, alcove, wall recess, or a suitable inclosure, whereby the disappearing bed will occupy a comparatively small 15 space and be invisible when not in use.

The bed forming the subject matter of this application includes a novel pivotal mounting, a foldable bed frame provided with tension devices preventing a sudden 20 movement of the bed frame, and automatically positioned feet for the bed frame when in a lowered or active position.

These structural devices and other matters will be hereinafter referred to, and reference will now be had to the drawing, 25 wherein

Figure 1 is a side elevation of the bed folded and swung within a compartment;

Fig. 2 is a plan of the bed showing the 30 compartment walls and the pivotal mounting of the bed in section, and

Fig. 3 is an enlarged elevation of a portion of the bed, partly broken away and partly in section illustrating an automatically positioned foot of the bed.

In the drawings, the reference numeral 1 denotes a wall having an opening or doorway 2, which may be an entrance to a closet 3. At one side of the doorway 2 is a hinged 40 door 4 and at the opposite side of the doorway is the pivotal mounting of the disappearing bed. The pivotal mounting comprises vertically alining bearings 5 and 6, the former on the floor or sill of the doorway 45 and the latter on the lintel or top wall of the doorway. The bearing 5 has anti-frictional balls 7 of a conventional form supporting a bracket 8 provided with an upright 9. The upper end of the upright 9 has a bracket 10 and a connecting member 11, said bracket and connecting member coöperating in holding an extension 12 of the upright 9 in the bearing 6. The upright 9 and the extension 12 thereof constitute a 50 pivotal mounting or swiveled support for the foldable bed structure and provides

clearance for the door knob of the door 4. The location of the mounting is essential, as will hereinafter appear.

The brackets 8 and 10 support a rectangular head piece 13, said brackets being connected to the top and bottom rails of the head piece, intermediate the sides thereof. The head piece contains a conventional panel and the side rails 14, at the lower ends 65 thereof, are provided with fittings 15 and 16 having forwardly projecting arms 17. On the outer ends of the arms 17 are fittings 18 and 19 supporting tubular legs 20. These legs are fixed in the fittings and the 70 lower ends thereof have fittings 21 for a transverse rod 22.

The fittings 18 have tension devices 29 which prevent a sudden and unexpected movement of the bed frame relative to its 75 support.

Slidable in the tubular legs 20 are feet 32 having the inner ends thereof connected by coiled retractile springs 34 to the inner or upper ends of the legs 20. The feet 32 80 have lateral extensions 35 extending through slots 36 in the upper ends of the tubular legs. The lateral extensions are engaged by anti-friction rollers 37 on outwardly projecting pins 38, carried by tension devices 29. 85

The back feet are retracted by the springs 34 when the raised or folded bed structure is swung on its pivotal mounting into the closet 3, and with the back feet yielding, there is no danger of carpets or rugs being 90 torn or otherwise injured.

The side rails 27 of the bed frame has the ends thereof connected by transverse spring supports 42 for a suitable bed spring 43. The side rails 27, at the head piece of the bed, are also connected by a mattress stop 44 having corner pieces 45 and bearing pieces 46, said bearing pieces being formed by cutting the mattress stop and bending the cut portions thereof forwardly to co-operate with the corner pieces 45 in supporting rods 47. Connected to the rods 47 and the transverse rod 22 are a plurality of coiled springs 48 and these springs are adapted to facilitate raising the bed frame 105 to a vertical or folded position, besides maintaining the bed frame in such position, as shown in Fig. 1.

The outer ends of the side rails 27 of the bed frame have a foot piece 49 provided 110 with a suitable panel and with foldable feet 50 connected by a transverse rod 51,

said foldable feet having ruled joint connections 52 with the foot piece, whereby said foldable feet can only move in one direction, as shown in Fig. 1.

5 As shown in Figs. 1 and 2 of the drawing, it is necessary to use a hinged door to close the doorway 2 and with the bed structure of greater width than the doorway, it is also necessary to locate the pivotal mounting of the bed structure adjacent to the side wall of a doorway, whereby first one portion of the bed structure can be swung through the doorway and then the remaining portion thereof. In this manner 10 the bed structure, when raised or folded, can assume a position with a portion thereof in parallelism with the outer side of the wall 1, or with another portion thereof in parallelism with the inner side of the wall 1, the first position representing the position which permits of the bed frame being lowered to a horizontal position and the bed used. The latter position, as shown in 15 Fig. 2, is that of the bed structure in an 20

inactive position, and it is possible for a person to enter the closet 3 by passing around the edge of the bed structure. 25

What I claim is:—

The combination with a wall having an opening adapted to be closed by a hinged door having a door knob actuated latch, of a pivotal mounting in the opening of said wall adjacent that wall of the opening to and from which the door knob edge of the door swings and comprising off-set uprights 30 providing clearance for the door knob of the hinged door, a head piece supported by said uprights, and a bed frame supported from said head piece and capable of being swung from a horizontal position to a vertical position in parallelism with said head piece. 35

In testimony whereof I affix my signature in presence of two witnesses.

LEWIS C. HUNTER.
